UNITED STATES PATENT OFFICE.

ALBERT SLATEN, OF MINNEAPOLIS, MINNESOTA.

NONDRIP VALVE.

Original application filed March 5, 1925, Serial No. 13,382. Divided and this application filed October 31, 1927. Serial No. 230,064.

My present invention relates to a valve and more particularly to a non-drip valve intended for general use, but especially adapted for use in connection with a cream-dispensing device.

The present application is a division of my co-pending application entitled "Cream dispensing device", filed March 5, 1925, under Serial Number 13,382 and allowed May 2, 1927, 10 patented November 29, 1927, No. 1,650,806.

In the accompanying drawings, which illustrate the invention, like characters indicate like parts throughout the several views.

Referring to the drawings:

15 Fig. 1 is a right side elevation of a cream measuring and valve-controlling assembly removed from a cream-dispensing device;

Fig. 2 is a plan view of the same;

20 Fig. 3 is a view partly in right side elevation and partly in central vertical section taken on the line 3—3 of Fig. 2, with some parts shown in different positions by means of broken lines and further illustrating the supply tank of the cream-dispensing device;

25 Fig. 4 is a view principally in section taken on the line 4—4 of Fig. 2; and Fig. 5 is a fragmentary perspective view of one of the guide arms and associated parts.

The numeral 4 indicates a fragment of 30 a cream supply tank from which cream may be drawn through a cup-like valve casing 5 mounted in a depression in the bottom of said tank and having a plurality of discharge ports 6. A valve 7 mounted in a seat in the 35 top of the valve casing 5 normally closes the discharge ports 6 leading from the tank 4.

The valve 7 is provided with a depending 40 stem 8 which works in a bore-like passage in the bottom of the valve casing 5. Said valve 45 7 is arranged to close with the cream pressure in the tank 4 and a leaf spring 9 is provided for yieldingly closing said valve.

At the front of the supply tank 4 is a cream-measuring and valve-controlling assembly 45 that includes a receptacle 10 having a cream-measuring compartment 11. A cover, not shown, will be provided for the receptacle 10. Formed with the receptacle 10 is an inclined trough 12 which extends below the supply tank 4 and under the valve casing 5. This trough 12 is detachably applied to the bottom of the tank 4 and arranged to receive cream from the supply tank 4 through the discharge ports 6 when the valve 7 is open 55 and convey the same into the measuring com-

partment 11. The receptacle 10 at its top is circumferentially expanded at 13 and its lower end is open and has mounted therein a sleeve-like member having a port 14. The walls of the port 14 at its upper end is beveled 60 to the walls of the compartment 11 and the lower end of the port is contracted and its walls beveled to form a valve seat 15.

A heavy piston-like non-drip valve 16 is adapted to enter the port 14 and engage its 65 walls and has a beveled lower end portion 17 which is adapted to directly rest on the seat 15 when the valve 16 is closed and seals the port 14. The under side of the valve 16 is recessed and terminates in a depending sharp 70 annular edge 18 which, when said valve is closed, is in the same plane with the sharp annular edge formed between the lower end of the valve seat 15 and the exterior wall of the sleeve-like member. Rigidly secured to the valve 16 at the axis thereof is an upper 75 standing valve stem 19 the upper end of which is pivoted to a pair of converging guide arms 20 pivoted at 21 to the sides of the trough 12 for vertical swinging movement.

To open the valve 16 by means of a cup, not shown, placed under the port 14 to receive the measured cream from the compartment 11, when the valve 16 is opened, there is provided a horizontal cup-engaging metal plate 22 located just back of the receptacle 10 and under the trough 12. This cup-engaging plate 22 has a pair of laterally spaced upright stems 23 slidably mounted in a pair of guide 85 tubes 24 which extend into the trough 12 through the bottom thereof. On the upper ends of the stems 23 are bifurcated heads 25 through which the arms 20 extend. From the heads 25 the cup-engaging plate 22 is 90 supported at the proper height in respect to the receptacle 10. By reference to Fig. 3 it is important to note that there is clearance 95 between the guide tubes 24 and the heads 25 so that the valve 16 will not be held from its seat 15 when moved to its closed position.

Secured to the under side of the cup-engaging plate 22 is a cushion mat 26 of rubber or any other suitable material which prevents the rim of the cup from coming in direct contact with said plate which might break or chip the same. A leaf spring 27 on the one side of the trough 12 engages the adjacent guide arm 20 and yieldingly holds the valve 16 closed.

To open the valve 7 to fill the compartment 11 with cream from the supply tank 4, there is provided a lever 28 intermediately pivoted on a shiftable fulcrum, in the form of a 5 crank 29, journaled in the sides of the trough 12. This crank 29 has on one of its ends outward of the trough 12 a long arm 30, the free end of which extends between the side of the trough 12 and an anchor plate 31 rigidly secured to said trough. The arm 30 is 10 adjustably secured to the anchor plate 31 by a set screw 32 which has screw-threaded engagement with said arm and works in a segmental slot 33 in the anchor plate 31. This 15 screw 32, when tightened, frictionally clamps the arm 30 onto the anchor plate 31 and holds the same where set. The short or inner end of the lever 28 extends under the headed lower end of the valve stem 8 for engagement there- 20 with to open said valve, as will presently appear.

The lever 28 is operated by a float 34 in the cream-measuring compartment 11 and is provided with an axial passage through which 25 the valve stem 19 loosely projects. The long or outer end of the lever 28 is bifurcated and connected to the float 34 by a pair of diametrically opposite upstanding apertured lugs 35 secured to said float and through which 30 the prongs of the bifurcated end of the lever 28 loosely extend. A guide sleeve 36 for the valve stem 19 is mounted in the axial passage in the float 34. When the measuring compartment 11 is empty and the valve 16 closed, 35 the float 34 rests on the top of said valve and holds the lever 28 in position to hold the valve 7 open for the discharge of cream from the supply tank 4 to the trough 12 where the same is conveyed to said compartment.

40 Operation.

It may be here stated that the cream-dispensing device above described in which the non-drip valve is embodied is especially 45 adapted for use in restaurants, hotels and the like for filling coffee or other beverage cups with a predetermined amount of cream or other liquid.

The operation of said cream-dispensing device may be briefly described as follows: Before filling the supply tank with cream, the cream-measuring and valve-controlling assembly is detached from the device so that the float-actuated lever 28 will not hold the 55 valve 7 open. After the tank is filled with cream, the cream-measuring and the valve-controlling assembly is replaced and the float 34 acting on the lever 28 will cause said lever to open the valve 7 and allow cream to escape 60 from the supply tank 4 through the ports 6 into the trough 12 where the same is conveyed to the measuring compartment 11, and at which time the valve 16 is, of course, closed. As the compartment is filled with cream, the 65 float 34 rises and gradually operates the lever

28 and allows the valve 7 to close partly by gravity and partly by the spring 9. By adjusting the arm 30, the fulcrum 29 for the lever 28 may be varied, at will, to regulate the opening of the valve 7 by the float 34 to 70 vary the amount of cream in the measuring compartment 11.

When it is desired to fill a cup with cream, the same is placed under the receptacle 10 and said cup lifted to engage and lift the 75 plate 22 which, acting through the stems 23, arms 20 and valve stem 19, opens the valve 16 and allows the cream in the compartment 11 to flow through the port 14 and into the cup held thereunder. After the cream in the 80 measuring compartment 11 has all escaped into the cup held thereunder, said cup is lowered to release the plate 22 and permit the valve 16 to close partly under the action of gravity and partly under the action of the 85 spring 27.

With the closing of the valve 16, the float 34 moves down the valve stem 19 and again operates the lever 28 to open the valve 7 and allow the escape of cream from the tank 4 90 to the trough 12 through the ports 6 and again fill the measuring compartment 11 until stopped by the closing of the valve 7 as the same is released by the movement of the lever 28 under the lifting action of the float 34. 95

The action of the non-drip valve 16 is highly important and in actual usage has overcome one of the primary objections to cream-dispensing devices now in use, which is the dripping of cream during the intervals 100 between the time cream is drawn from the dispensing device.

By making the under side of the valve 16 concave and terminating the same in a sharp annular edge 18, cream will not adhere to the bottom of said valve by capillary attraction, but will collect on said sharp annular edge. During the closing movement of the valve 16 which is with a fast piston-like action due to the weight of said valve and the spring 27, a 110 short blast of air is produced by the entrance of said valve into the port 14 that clears the walls of said port, valve seat 15 and the valve 16 of any liquid thereon and shoots the same from said port and valve seat into the cup held thereunder, thus preventing dripping of the liquid after the valve 16 is closed. Any liquid on the valve 16 will quickly collect on its sharp cylindrical edge and will be easily shot therefrom into the cup. 115 120

What I claim is:

1. In a liquid-dispensing device, the combination with a compartment having a discharge port provided with a valve seat at its delivery end, of a piston-like acting valve for engaging said seat and closing said port, and means for giving said valve, when open, a quick downward movement to produce a blast of air at the time said valve enters the discharge port to clear the walls of said port, 125 130

valve seat and valve from liquid and shoot the same from said port and valve seat.

2. The structure defined in claim 1 in which the lower end of the valve is recessed 5 and terminates in a sharp edge.

3. In a liquid-dispensing device, the combination with a compartment having a discharge port, said discharge port having an internal contracted conical wall affording a 10 valve seat at its delivery end, of a piston-like acting valve having a conical lower end for engaging said valve seat and closing the discharge port, and means for giving said valve, when open, a quick downward movement to 15 produce a blast of air at the time said valve enters the discharge port to clear the walls of said port, valve seat and valve from liquid and shoot the same from said port and valve seat.

20 4. The structure defined in claim 3 in which the lower end of said valve is recessed and terminates in a sharp edge.

5. The structure defined in claim 3 in which the lower end of said valve is recessed and 25 terminates in a sharp edge, said sharp edge when the valve is closed being in substan-

tially the same plane as the lower end of said port.

6. A device of the class described comprising a compartment having a discharge port 30 provided with a valve seat and a piston-like acting valve for engaging the valve seat and closing the discharge port, said valve when open being under strain to close with a quick downward movement and produce a blast of 35 air at the time said valve enters the discharge port to clear the walls of said port, and valve seat, the lower end of said valve having a sharp depending annular edge.

7. A device of the class described comprising a compartment having a discharge port the wall of which forms an inwardly and 40 downwardly beveled valve seat, said wall forming with the exterior wall of the compartment a sharp annular edge, and a valve 45 for closing the port, having its lower end formed so as to rest on the valve seat and terminate in a sharp annular edge that is substantially aligned with the sharp edge of the valve seat when the valve is closed. 50

In testimony whereof I affix my signature.
ALBERT SLATEN.
